UNITED STATES PATENT OFFICE.

VLADIMIR S. BEKOFSKY, OF NEW YORK, N. Y.

STOVE.

SPECIFICATION forming part of Letters Patent No. 358,640, dated March 1, 1887.

Application filed July 1, 1886. Serial No. 206,813. (No model.)

To all whom it may concern:

Be it known that I, VLADIMIR S. BEKOF-
SKY, of the city, county, and State of New
York, have invented a new and Improved
5 Stove, of which the following is a full, clear,
and exact description.

My invention consists of the construction of
a stove having a central downwardly-projecting
chimney-flue.

10 Reference is to be had to the accompanying
drawings, forming a part of this specification,
in which similar letters of reference indicate
corresponding parts in all the figures.

Figure 1 is a sectional plan view taken on
15 the line $x-x$ of Fig. 3. Fig. 2 is a similar view
on the line $y-y$, Fig. 3. Fig. 3 is a central sec-
tional elevation on line $z-z$, Fig. 2; and Fig. 4
is a transverse sectional elevation on line $z'-z'$
20 of Fig. 1. Fig. 5 is a transverse sectional ele-
vation parallel with the line $z-z$, Fig. 2, and
through the flues $P P P^2$.

The stove is constructed to form the fire-
box A, and the three ovens B C D, and the
central main outlet-flue, E. Over the tops of
25 the ovens is placed the plate F, upon the up-
per surface of which are formed the flanges G
G and cross-flanges H, and upon these flanges
and the upper edges of the outer main walls
of the stove is placed the top plate, I, in which
30 the stove-holes I' are formed, as in ordinary
stoves, and which, together with the plate F,
form the flame passage or space J over the
ovens. The flanges G H deflect the flame and
heat issuing from the fire-box A into the flame
35 passage or space J, and these flanges, together
with the top plate, I, form a return-passage,
J', for directing the products of combustion
to the main flue E. The oven B is formed with
a double wall and bottom arranged to form
40 the surrounding space K L M, and between
the flanges G G is fitted a damper, N, which,
when raised to vertical position by rod N' or
otherwise, closes the passage J' to the flue E,
and causes the heat and products of combus-
45 tion to pass from the flame-space J down pas-
sage K, back through the bottom space, L,
and up passage M to passage J', thence to the
flue E.

When the damper N is placed in horizontal
50 position, it closes the passage M, so that if the
dampers O O' are not closed, as hereinafter
described, the products of combustion will

pass directly from the space J to the passage
J', and thence down the flue E to the horizon-
tal flue E', which may be connected directly, 55
or by means of a pipe, to an ordinary chimney-
flue of a building.

At the back of the oven C are formed the
three vertical flues P P P², (see Figs. 2 and 4,)
and below this oven is formed the space P'. 60
The flues P P P² connect at their lower ends
with the space P', and in the space P' are fit-
ted the two short deflecting-plates p p, which
serve to deflect the products of combustion
entering space P' from the two flues P out into 65
the space P', to heat the entire bottom of the
oven C before returning by the return-flue P²,
as indicated by the dotted arrows in Fig. 2.

At the back of the oven D are formed the
three vertical flues Q Q Q², which communi- 70
cate at their lower ends with the space Q' be-
low the oven D, and in the space Q' are fitted
the two short deflecting-plates q q, which serve
to deflect the heat and products of combustion
entering space Q' from the flues Q Q through- 75
out the bottom of the oven before returning
through the central flue, Q².

The damper O (above mentioned) is fitted
in the partition that separates the flue P² from
the main central flue, E, and is so arranged 80
that when brought to horizontal position by
the lever a and connecting-rod b, or otherwise,
it closes or stands across both flues E P², and
puts them into communication with each other
both above and below the damper, the damper 85
being centrally pivoted.

The damper O' is fitted in the partition that
separates the main flue E from the flue Q², and
is arranged a short distance below the damper
O, as shown clearly in Fig. 4, and when brought 90
to horizontal position by the lever a' and con-
necting-rod b', or otherwise, it closes or stands
across both flues E Q², and at the same time
puts these flues into communication with each
other both above and below the damper, as 95
will be understood from the dotted lines in
Fig. 4.

By this arrangement, by opening the damper
N in the passage J', (dampers O O' being closed,) 100
the ovens will not be materially heated, as the
heat and products of combustion pass from
the flame-space J directly to passage J' and
out the main flue E; but by closing damper N
(dampers O O' being still closed) the products

of combustion will pass from the flame-space J around the main large oven B, through spaces K L M, thence to space J' and main flue E. Now, by opening damper O the main flue E will be closed, and the flue P² will also be closed, and these two flues E P² will be put in communication with each other, and also, through the upper part of the flue P², cut off by the damper O, the main flue E will be 5 put in communication with the side vertical flues, P P, so that the products of combustion entering the main flue E from the passage J' will strike the upper surface of the damper O and be deflected into the two side vertical 10 flues, P P, down which they will pass to the space P' below the oven C, and pass around the ends of the deflecting-plates p, and return and enter the central flue, P², up which they will pass until they strike the under surface 15 of the damper O, which will deflect the products of combustion again into the main flue E, through which they will pass out of the stove. Proceeding from the entrance of the products of combustion to the main flue E 20 from flue P² below the damper O, if damper O' be now opened, the flue E will be again cut off and put into communication with the central vertical passage, Q², and also through this 25 passage with the two side flues, Q Q. The products of combustion now will pass from flue P² across the main flue E, and enter the 30 passages Q² and Q Q, down which latter they will pass to the space Q' below the oven D. They will circulate through this space and 35 return between the short deflecting-plates q q to the central flue, Q², up which they will ascend and enter the main flue E below the damper O', and pass out of the stove. In this manner 40 all of the ovens, or any one or none of them, may be especially heated in their respective surrounding spaces, and the products of combustion passing from one oven to another are retained a long time in the stove, so that all of the available heat is utilized, resulting in economy of fuel.

The rods a a' and b b', which operate the dampers O O', are inclosed by the side spaces,

R R, between the flues P Q, and at one end of the fire-box A is formed the water-heating compartment W, and below the horizontal flue E' is formed a jacket or open space, E', through which air has free circulation throughout its whole length, so there will be no danger of overheating or burning the floor from the flue E'. 50

By the use of the flanges G G H the flame is evenly spread under the whole top plate, I, and consequently the heat will be equally communicated to all the kettles or pans placed in or upon the stove, so there will be an equal heating effect at all parts of the top of the stove. 55

Having thus described my invention, what I claim as new, and desire to secure by Letters Patent, is—

1. A stove constructed to form the downwardly-projecting main flue E, the side vertical flues, P P, and return-flue P², in combination with the damper O, arranged centrally in an opening in the partition between the flues E P², and centrally pivoted to close said flues E P², and to put them into communication with each other both above and below the damper, substantially as described. 65

2. A stove constructed to form the main flue E, the two sets of vertical flues P Q, and the return-flues P² Q², in combination with the dampers O O', arranged one above the other in openings formed, respectively, in the partitions between the flue E and P² and the flue E and Q², the dampers being centrally pivoted, 70 substantially as described. 75

3. A stove constructed with the fire-box A, flame-space J, ovens B C D, having surrounding spaces, the dampered passage J', and vertical central main flue, E, in combination with the passage K, vertical flues P Q, return-flues P² Q², and two dampers, O O', set one above the other in the sides of the main flue E, substantially as and for the purposes set forth. 80
